UNITED STATES PATENT OFFICE

ALBERT B. McCUTCHEON, OF MIDDLETOWN, CONNECTICUT

DESIGN FOR A SPINET LAMP SUPPORT

Application filed March 27, 1931. Serial No. 39,272. Term of patent 3½ years.

To all whom it may concern:

Be it known that I, ALBERT B. McCUTCHEON, a citizen of the United States of America, residing at Middletown, in the county of Middlesex and State of Connecticut, have invented a new, original, and ornamental Design for Spinet Lamp Support, of which the following is a specification, reference being had to the accompanying drawing, forming part thereof.

The figure is a view in perspective of a spinet lamp support, showing my new design.

I claim:—

The ornamental design for a spinet lamp support, as shown.

ALBERT B. McCUTCHEON.
